UNITED STATES PATENT OFFICE.

ALBERT BULLOCK, OF LOS ANGELES, CALIFORNIA.

WELL-DRILLING APPARATUS.

Application filed March 28, 1921. Serial No. 456,325.

To all whom it may concern:

Be it known that I, ALBERT BULLOCK, a resident of Los Angeles, in the county of Los Angeles and State of California, have invented new and useful Well-Drilling Apparatus, of which the following is a specification.

This invention relates to deep well drilling and particularly relates to apparatus used in both rotary and reciprocating drilling operations.

It is an object of my invention to provide an apparatus for the drilling of wells in which the operating power is applied at a point very near to the drilling tool, thereby eliminating a larger portion of the friction as encountered in present methods of drilling and consequently reducing expenditures for the replacement of broken parts to a minimum, as well as materially reducing the amount of power being consumed in the operation of the drilling tools.

In the present methods of rotary drilling, much delay is caused by the breaking of drills and drill tubing and an enormous overconsumption of power is caused by the friction between the drill tubing and the soft mud that is being washed out and carried up through the well by the flow of water which is used for such purposes.

It is a further object of my invention to provide an apparatus, the use of which will make unnecessary the employment of surface revolving and reciprocating apparatus and great lengths of drill tubing, with the result that losses due to breakage and loss of parts will be overcome and a very material efficiency of operation will therefore become evident.

I attain the objects of my invention in the use of a device which may be inserted into a well in the process of drilling and which will have incorporated therein means for revolving and reciprocating a tool shank adapted to receive any of the standard forms of drilling tools.

With reference to the drawings, which are for illustrative purposes only, and are intended to present merely an embodiment of my invention:

Fig. 1. is a somewhat diagrammatic view of the apparatus I employ, as it is used in connection with the sinking of the well casing as the drilling progresses.

Fig. 2. is a section taken vertically through the apparatus and casing shoe used in connection with the drilling method illustrated in Fig. 1.

Fig. 3. is a detail of cable drum, showing manner in which the electric conductors of the cable are connected with an exterior circuit.

Fig. 4. is a diagrammatic view showing the apparatus in application to the sinking of wells without the use of well casing.

Fig. 5. is a section through the apparatus taken on a plane represented by the line 5-5 of Fig. 2.

Fig. 6. is an elevational detail of the tool shank and conical roller bearing. This detail is provided to better illustrate the manner in which reciprocative movement is imparted to the tool shank.

Fig. 7. is a section of the apparatus taken on a plane represented by the line 7-7 of Fig. 2.

Fig. 8. is a section through the apparatus and the casing shoe, and is taken on a plane represented by the line 8-8 of Fig. 2.

Fig. 9. is a fragmentary view of the cable I employ and illustrates the manner in which the hose is at intervals attached to the cable by clamps.

Fig. 10. is a cross section through the cable shown in Fig. 9.

Similar characters refer to similar parts throughout the several views of the drawings.

In Fig. 1 a drilling tool 11 embodying my invention is shown in operation in a well casing 12, the lower end of which constitutes a special form of casing shoe to prevent the counter rotation of the tool 11 as will hereinafter be set forth. In certain instances where the condition of the strata will permit it is customary to drill to the full depth of the well before inserting the well casing and in such instances a leader casing 25 is used to carry the drilling operation through the soft soil and sand. The diagrammatic illustration Fig. 4 shows my drilling tool in this application.

The apparatus I employ comprises essentially a shell 11^a in which is placed a motor consisting of a revolvable armature 13 and a stationary field 14. The armature punchings are mounted on a hollow shaft 12^a hav-

ing mounted on its lower end a gear 15 in mesh with planetary gears 16 mounted on pins 18 which extend from a plate 20. The planetary gears 16 are confined by and are in mesh with a ring gear 17.

The plate 20 which mounts the planetary gears has downwardly extending therefrom a short shaft 22 on which is mounted another gear 15' and has surrounding it planetary gears 16' and an internal ring gear 17'. A plate 23 mounting the lower set of planetary gears 16' has extending downwardly therefrom a short shaft 30 which extends through a suitable bearing 26 and which is slotted to engage with an extension 27 protruding from the drill shank 32 from which upwardly extends a water tube 31.

The drill shank 32 is supported in a bearing 39 which is also formed to provide a cone plate and forms with a plate 40, mounted on the drill shank 32, and the conical rollers 41, a roller bearing to resist the reaction of the drill shank when in operation. To prevent the inflow of water I provide packing 42 which is enclosed and put under pressure by a gland nut 43. The drill shank is provided with a standard female tool joint 44 and water supplied through the water tube 31 is delivered to the tool through a passage 45 formed within the drill shank 32.

By the gearing arrangement heretofore described, the motor speed may be reduced to that desired for drilling purposes and any number of sets of reduction gears may be employed to accomplish this purpose in addition to the two sets I have shown.

The drilling tool is lowered into the well and supported therein by a cable 50 gripped by a clamp 51 mounted on the top of the tool. I desire to direct especial attention to the construction of the cable I employ, as it embodies new and distinctive features in the provision of a weight sustaining and electric current conducting means. As shown in Figures 9 and 10, I use a cable which provides a core 100 formed of stranded insulated wires 101 twisted to provide resiliency when the cable is passing over a sheave, and the weight sustaining element consists of an exterior winding of stranded cables 102. The weight sustaining structure of the cable 50 is discontinued upon passing through the clamp 51 and the core 100 comprising the insulated conductors 101 is passed down through a gland 52 into the interior of the drilling tool.

Water to lubricate the drilling bit and to carry off the cuttings therefrom is supplied through a hose 53; adapted to be supported upon the cable 50 by clamps 102, and provided in suitable lengths and joined by standard couplings; and which makes connection with my drilling tool as indicated at 54 discharging into a chamber 55 formed in the cup member 56 by a parti-

tion 57. It will be noticed that the water tube 31 enters the chamber 55 through a stuffing box 60 and that the water delivered into the chamber 55 through the hose 53 may pass through the water tube 31 into the passage 45 of the drill shank from whence it is supplied to whatever drill bit is being used.

Within the casing of the drilling tool the wires 101 are carried down through a chamber 58 formed in the cup 56 and passing through insulators 61 and 62 are connected to brushes 69 which bear upon a commutator 68 having connection with the different windings of the armature. 80

When drilling at great depths the pressure of the column of water acting upon the exterior of the tool would be sufficient to overcome the efficiency of the packing glands and water would be forced into the interior of said tool. In order that an interior pressure may be created to resist the influx of water, I provide a container 65 which may be filled with some substance, such as anhydrous ammonia, and which is connected to a pressure regulator 66 through piping 67. This pressure regulator 66 is preferably of the diaphragm type and may be set to maintain the interior of the tool at a slightly higher pressure than exists on the exterior thereby maintaining a slight overflowing tendency through the stuffing boxes. 95

The cable 50 extending over a sheave 75 is adapted to be wound upon a drum 76 and connection is made through collection rings 77, 78 and 79 to an exterior circuit 80, 81 and 82. The connection between the cable 50 and the collector rings is illustrated diagrammatically at 83, 84 and 85 in Fig. 3. 105

I have found that an upward and downward reciprocation of the drill bit in combination with the relation of same is productive of much greater speed in removing material and I provide for a combination of these movements by a cam form of cone plate 39 as illustrated in Fig. 6, and I use a spring 90 acting between the lower cone plate 40 and the bearing 91 to hold the drill shank normally in a raised position. 110 The plate 39 is contoured 70 on its conical face 71 as illustrated; and the rollers 41 alternately mount and recede thereon, thereby providing the desired reciprocation. 115

In the application wherein it is necessary to sink the well casing as the drilling progresses, I provide the arrangement illustrated in Figures 1 and 2 wherein I show a casing shoe 12 provided with interiorally extending lugs 110 which are adapted to engage outwardly extending lugs 109 on the shell 11* and thereby prevent any counter-rotation of the drilling tool and also provide a guiding means for same. 125

It is quite often that conditions permit 130

of sinking the hole to great depths before it becomes necessary to insert casing. In such instances I adapt my invention as illustrated in Fig. 4. To prevent the counter 5 rotation and to guide the tool on its downward course I use standard drill tubing 120 suitably attached 121 to the tool 11. In this application the drill tubing serves as a means of conveying the wash out water 10 to its point of application and is attached to an exterior supply, not shown, as indicated at 122, and as the increased capacity of the drill tubing permits a greater flow of water, I also provide additional distributing pipes 123 to deliver the water to the drill bit.

The cable I employ has a much broader application than that which is shown, as in the case of electrically operated elevators. 20 By its employment all necessity for under-hanging cables as are now in use would become eliminated and a more satisfactory installation would result both from the standpoint of economy and engineering 25 practice.

As my invention I claim:

1. In well drilling apparatus, the combination of: a drill bit; means for suspending said drill bit in operating position, 30 and means between said drill bit and said suspending means adapted to continuously rotate and reciprocate said drill bit.

2. In well drilling apparatus, the combination of: a drill bit, a cable comprising a 35 weight sustaining and current conducting element; and means between said drill bit and said cable adapted to continuously rotate and reciprocate said drill bit.

3. In a well drilling tool: a shell; a drill 40 bit; a drill shank rotatably mounted within said shell and adapted to receive said drill bit; a motor within said shell; gears between said drill shank and said motor to rotate said drill shank; a water supply connection from an exterior source to said well 45 drilling tool; and means for conveying water to said drill bit.

4. In a well drilling tool: a shell; a drill 50 bit; a drill shank rotatably mounted within said shell and adapted to receive said drill bit; a motor within said shell; gears between said drill shank and said motor to rotate said drill shank; a water supply connection from an exterior source to said well 55 drilling tool; means for conveying water to said drill bit; a pressure tank within said shell; and a diaphragm valve adapted to maintain an equal or slightly greater pressure within said shell than exists on the outside thereof by discharging a portion 60 of the contents of said pressure tank into the interior of said shell.

5. In a well drilling tool: a shell; a drill 65 bit; a drill shank rotatably mounted within said shell and adapted to receive said drill

bit; a motor within said shell; gears between said drill shank and said motor to rotate said drill shank; a water supply connection from an exterior source to said well drilling tool; means for conveying water to 70 said drill bit; a pressure tank within said shell; a diaphragm valve adapted to maintain an equal or slightly greater pressure within said shell than exists on the outside 75 thereof by discharging a portion of the contents of said pressure tank into the interior of said shell; a cone plate mounted on said drill shank; a cone plate providing an undulating conical surface; and cone rollers adapted to operate between said cone plates. 80

6. In a well drilling tool: a shell; a drill bit; a drill shank rotatably mounted within said shell and adapted to receive said drill bit; a motor within said shell; gears between said drill shank and said motor to 85 rotate said drill shank; a water supply connection from an exterior source to said well drilling tool; means for conveying water to said drill bit; a pressure tank within said shell; a diaphragm valve adapted to maintain an equal or slightly greater pressure within said shell than exists on the outside 90 thereof by discharging a portion of the contents of said pressure tank into the interior of said shell; a cone plate mounted on said drill shank; a cone plate providing an undulating conical surface; cone rollers adapted to operate between said cone plates; and means to guide and prevent the counter-rotation of said tool when in operation. 95

7. In a device of the class described, the combination of: a shell; rotative and reciprocative mechanism within said shell; and means contained within said shell for maintaining a pressure within said shell substantially equal to the external pressure acting upon said shell. 100

8. In a device of the class described, the combination of: a shell; operative mechanism within said shell; and means contained within said shell for maintaining a pressure within said shell substantially equal to the external pressure acting upon said shell. 105

9. In a device of the class described, the combination of: a shell; rotative and reciprocative mechanism within said shell; and diaphragm controlled means for maintaining a pressure within said shell substantially equal to the external pressure acting upon said shell. 110

10. In a device of the class described, the combination of: a shell; operative mechanism within said shell; and diaphragm controlled means for maintaining a pressure within said shell substantially equal to the external pressure acting upon said shell. 115

11. In a device of the class described, the combination of: a shell; rotative and reciprocative mechanism within said shell; diaphragm controlled means for maintaining 120

a pressure within said shell substantially equal to the external pressure acting upon said shell; and means for carrying a supply of lubricating fluid to the drill bit operated by said device.

Signed at Los Angeles, in the county of Los Angeles, and State of California, in

the presence of two subscribing witnesses this eighteenth day of March, 1921.

ALBERT BULLOCK.
